UNITED STATES PATENT OFFICE

ROGER CONNOR, NELSON S. WELK AND DAVID R. ZENNER, OF ATHENS, OHIO, ASSIGNEES
TO THE MCBEE BINDER COMPANY, OF ATHENS, OHIO

LOOSE-LEAF BINDER

Application filed January 24, 1931. Serial No. 511,070.

This invention relates to an improvement in binders and more particularly, to that type of binder employed in connection with loose leaves having suitable perforations near one marginal edge thereof.

5 An object of the invention is to provide a binder, employing two separate binder members and covers, together with binding posts which are completely detachable from the binder covers.

10 Another object is to provide one of the binder members with locking mechanism adapted to engage the binding posts at any desired point longitudinally thereof to hold 15 the same in any desired position of adjustment.

The binder, forming the subject of this invention, is employed in connection with the posting stand, described in our pending 20 application for Letters Patent filed December 22, 1930, Serial No. 504,130. As set forth in said application, it is essential for the best operation of the posting stand, that the binding posts be entirely removed from the 25 binder covers during the operation of posting.

In the drawings,

Figure 1 is a partial plan view of the top binder cover, showing the top binder member;

Figure 2 is a vertical end view of the binder filled with loose leaves of paper;

Figure 3 is a partial plan view of the bottom binder cover, showing the bottom binder member;

Figure 4 is a section on the line 4-4 of Figure 2;

Figure 5 is a section on the line 5-5 of Figure 3;

Figure 6 is a section on the line 6-6 of Figure 2;

Figure 7 is a section on the line 7-7 of Figure 1; and

Figure 8 is a section on the line 7-7 of Figure 1 showing the post locking mechanism in inoperative position.

The top binder cover 1 and its complementary hollow binder member 2 and the bottom cover 3 together with its complementary hollow binder member 4 are constructed in

accordance with the disclosure of Patent 1,697,634, Robert J. Copeland, patented January 1, 1929. Our invention is concerned principally with the post locking mechanisms contained within the hollow binder members 55 2 and 4.

The loose leaves of paper which are to be bound together and shown at 8 and are held between the binder covers 1 and 3 by the binding posts 5 and 6 together with the associated locking mechanisms. The binding posts are integrally united by a post bar 7, riveted or otherwise secured thereto. By this arrangement, when desired, the pair of binding posts may be inserted or removed as a unit, 60 leaving the bottom binder cover free of any rigidly attached posts, so common in prior constructions.

Referring to Figures 4 and 5, which are sectional views of the bottom binder member 70 4, it will be seen that there are four openings 9, 9, 10, 10 extending through the parallel walls of said binder member. These openings are of such a diameter as to permit free and easy entry of the posts 5 and 6. The bottom wall of the binder member has an inward depression 11, therein to accommodate the post bar 7 when the posts are in locked position. A leaf spring 12, riveted to the binder member, intervenes between the binder member and the post bar and serves to push out the posts 5 and 6 and the post bar 7 when the locking mechanism is released. The locking mechanism consists of a flat bar or bolt 13, provided with locking openings 75 14, 14, therein, through which the binder posts are inserted. The binder posts are provided with grooves 15, 15 whose diameters are slightly less than the diameters of the binding posts. The bar or bolt 13 is normally urged to operative or locking position by means of a spring 16 held in contact with the bar or bolt by means of the projection 17. The spring is also brought under compression by the end piece 18 which serves also to fill in 80 the opening formed at the end of the tubular binder member. The bar or bolt 13 is also provided with upstruck tongues 19 which serve to keep said bar or bolt substantially in the same operating plane at all times. The 85 100

opposite end of the binder member 4 is closed by means of a member 20, provided with openings 21 and 22 therein, adapted to receive a freely movable pusher bar or key 23. This pusher bar engages the bar or bolt 13 and when the former is depressed by the operator, the bar or bolt is moved laterally against the compression of the spring 16, thereby permitting the marginal edges of the openings 14 to be removed from the grooves 15 whereupon the leaf spring 12 will be released and the posts 5 and 6 will be flung slightly free of the binder member 4. When the posts are in locked position, the post bar 7 rests in the depression 11, thereby presenting a smooth surface on the back of the lower binder member.

The above described operation maintains only in so far as the lower binder member 20 and the binding posts are concerned. The upper binder member 2 is also equipped with locking mechanism and this mechanism must first be released before the posts may be removed from the lower binder member locking 25 mechanism.

Since the upper binder member is to be adjustable longitudinally of the posts to accommodate various binder capacities, it has been found necessary to change the locking mechanism somewhat. To this end, locking levers 24, 24, of the configuration shown in Figure 6 are provided. These locking levers are provided with two downwardly depending lugs 25, 25, fitting freely in openings 35 26, 26, provided in the lower wall of the binder member. This arrangement constitutes a pivotal or hinge connection about which the levers 24 may pivot. These levers are provided with through openings 27, 27 40 which align themselves with the openings 28 extending through the walls of the binder member, whenever the levers are in inoperative or unlocked positions. The levers are urged to inoperative position by means of 45 small springs 29, 29, secured to the levers in the manner shown and inserted between the upper surface of the levers and the inner face of the upper wall of the binder member 2. The two levers 24 are urged to operative or 50 locking position by a common means 30, comprising a flat bar or bolt and having thereon raised portions or cams 31. Secured to the common means 30 is a depressible metal member 32, secured thereto by a rivet and carrying at its free end a button 33, supported upon a stud 34. This stud is slightly greater in length than the wall of the member 2 is thick and at the point where the stud is secured to the metal member 32, contact is 55 made between the member 32 and the wall due to the fact that the metal member is resilient enough to urge the stud upwardly. The button 33 is carried at the free end of 60 the stud. This stud normally rests in the opening 35 which is larger in diameter than

the stud 34 and merges into an elongated straight slot 36 which slot has a width substantially equal to the diameter of the stud but upon depressing the member 32 and urging the button 33 to the right, Figure 8, said 70 stud travels in the slot 36, until it has reached the confining limits of said slot, whereupon the bar or bolt 30 carrying the cams 31 has functioned to actuate the levers 24 by raising their free ends so that they are now in operative or locking position. The button 33 must be depressed before the locking mechanism can be operated, due to the frictional contact between the member 32 and the wall. If the button 33 and stud 34 could slide rather freely 80 in the slot 36, as is common in most constructions, mere dropping of the binder would be sufficient to disengage the locking mechanism. By providing the contact between the wall of the member 2 and the member 32, 85 there is just enough contact to prevent accidental dislodgment of the locking mechanism. In this position the openings 27 are out of alignment with openings 28 and consequently the marginal edges of the openings 90 27 serve to bind or grip the posts 5 and 6 which have been inserted through openings 27 and 28. Thus it may be seen that the top binder cover and binder member may, in this manner, be adjusted at any point longitudinally of the binding posts 5 and 6. The gripping action is certain and the loose leaves are retained securely between the binder covers.

To remove the posts and covers so that the 100 contents of the binder will be available for posting, as set forth in our pending application referred to above, it is only necessary to first unlock the mechanism shown in Figure 7, by moving the button to the left, thereby 105 releasing the levers 24 and thereupon releasing the locking mechanism shown in Figure 5, by depressing the plunger 23. The posts may then be easily removed by hand and since they are united by the post bar 7, the 110 posts come out as a unit.

We claim:

1. In a binder, the combination of cover-boards each provided with a hollow binder member having openings from face to face for the passage therethrough of binding posts; a plurality of binding posts; pivoted locking mechanisms mounted in one of said hollow binder members for gripping or binding said posts at any desired point in the length of said posts and sliding locking mechanism mounted in the other of said hollow binder members which grips said posts only at one point of their length.

2. In combination, a pair of hollow binder members each provided internally with post-locking mechanism and provided with openings therethrough; binding posts passing through said openings and the holes in the leaves to be bound, the ends of the posts at

one end being united by a bar, the other ends of the posts being pointed.

3. In a binder, in combination with a pair of binding posts; a hollow binder member having a plurality of holes therethrough adapted to receive and movable lengthwise of said posts; a locking mechanism carried by said binder member comprising a pair of levers each pivotally secured to the bottom wall and lying between the parallel top and bottom walls of said hollow binder member, each of said levers having a hole therethrough normally alined with the corresponding holes in the hollow binder member adapted to receive the corresponding binding posts and a common means for operating each such lever upon its pivotal connection to cause the hole therethrough to be forced out of alinement with the holes in the hollow binder member and thus bind the binding post between such lever and the edges of the holes in said top and bottom walls of said hollow binder member and a spring for restoring each such lever to its inoperative position.

25 4. In a binder, in combination with a pair of binding posts; a hollow binder member having a plurality of holes therethrough adapted to receive and movable lengthwise of said posts; a locking mechanism carried by 30 said binder member comprising a pair of levers each pivotally secured to the bottom wall and lying between the parallel top and bottom walls of said hollow binder member, each of said levers having a hole there- 35 though normally alined with the corre- sponding holes in the hollow binder member adapted to receive the corresponding binding posts and a common means for operating each such lever upon its pivotal connection 40 to cause the hole therethrough to be forced out of alinement with the holes in the hollow binder member and thus bind the binding post between such lever and the edges of the 45 holes in said top and bottom walls of said hollow binder member, and a spring for restor- 50 ing each such lever to its inoperative position, said common operating means comprising a member supported by a wall of said hollow binder member and having a plurality of cam 55 portions therein adapted to engage said le- vers when said operating means is operated from outside the hollow binder member.

In testimony whereof we affix our signatures.

55 ROGER CONNOR,
